MACHINE FOR PACKING EGGS

Harold J. Mumma, Riverside, Calif., assignor to Food Machinery and Chemical Corporation, San Jose, Calif., a corporation of Delaware

Filed Dec. 23, 1954, Ser. No. 477,361

5 Claims. (Cl. 221—221)

The present invention relates to machines for packing eggs. More particularly the present invention relates to machines for packing eggs into lidded cartons that provide two consecutive parallel rows of pockets each adapted to receive an individual egg with its main axis disposed vertically.

It is an object of the present invention to provide a machine that is operable to fill the individual pockets of a carton with eggs.

Another object is to provide a machine, of the type referred to, that is of simple construction yet dependable in operation.

Another object is to provide mechanism, in a magazine adapted to receive a stack of superposed lidded cartons, that is dependably operable to discharge the cartons individually from the magazine onto a conveyor underneath.

Another object is to provide a magazine that is adapted to receive a stack of superposed lidded cartons and which is operable to deposit the lowest carton in the stack onto a conveyor underneath while dependably retaining the remaining cartons in the stack within the magazine.

Another object is to provide a machine, of the type referred to, that is operable to successively place the consecutive pocket rows of a lidded carton into egg receiving position relative to an egg supply conveyor.

Another object is to provide a machine to which a stack of lidded cartons is delivered and past which a procession of eggs may be conducted on a suitable egg supply conveyor and which is operable to separate the cartons from each other and place them with their pocket rows successively into egg receiving position below the egg supply conveyor so that the eggs may be dropped from said conveyor into the individual pockets of the cartons.

Another object is to provide a simple yet dependably operating conveyor for cartons of the type referred to.

Another object is to provide a carton supply conveyor, for egg packing machines of the type referred to, that is adapted to firmly grip cartons delivered thereto and to hold them securely in position as the conveyor advances.

Another object is to provide a carton supply conveyor with means automatically effective to hold a carton deposited onto the conveyor securely on the conveyor during advancement thereof.

Another object is to provide a drive mechanism, for carton supply conveyors of the type referred to, that operates to advance the conveyor alternately at a relatively slow and a relatively fast rate of speed.

Another object is to provide intermittent drive mechanism, for carton supply conveyors of the type referred to, that operates to advance the conveyor alternately over a shorter and a longer distance.

Another object is to provide a drive mechanism, for carton supply conveyors of the type referred to, that operates to advance the conveyor alternately over a relatively short distance at a relatively slow rate of speed and over a relatively long distance at a relatively fast rate of speed.

Another object is to provide an intermittent drive mechanism, for the carton supply conveyor of an egg packing machine of the type referred to, that operates to advance the cartons alternately at a slow rate of speed over the limited distance necessary to place the second pocket row of a carton into egg receiving position after the first pocket row of said carton has been filled with eggs, and

2

at a fast rate of speed over the relatively long distance necessary to place the first pocket row of a directly succeeding carton on the conveyor into egg receiving position.

These and other objects of the present invention will become apparent from the following description of the accompanying drawings, which illustrate a preferred embodiment thereof, and wherein:

FIG. 1 is a side elevation of an egg packing machine embodying my invention.

10 FIG. 2 is an end elevation of the egg packing machine illustrated in FIG. 1.

FIG. 3 is a longitudinal section through the egg packing machine taken along line 3—3 of FIG. 2 and viewed in the direction of the arrows associated with said line.

15 FIGS. 4, 5, and 6 are fragmentary longitudinal sections through the egg packing machine taken along lines 4—4, 5—5, and 6—6, respectively, of FIG. 2.

FIGS. 7 and 8 are fragmentary longitudinal sections through the egg packing machine taken along the line 20 7—8 of FIG. 2, and illustrating the drive mechanism for the carton supply conveyor of the machine.

FIGS. 9A, 9B, 9C and 9D are schematic longitudinal sections through the egg packing machine, similar to FIGS. 7 and 8, illustrating consecutive operational positions of the drive mechanism for the carton supply conveyor.

FIG. 10 is an exploded perspective of the conveyor drive mechanism illustrated in FIGS. 7 and 8.

FIG. 11 is a fragmentary perspective of the carton 30 magazine and the carton supply conveyor.

FIG. 12 is another fragmentary perspective of the carton supply conveyor and of mechanism for delivering a carton from the magazine of the machine onto said conveyor.

FIG. 14 is a fragmentary transverse section through the upper run of the carton supply conveyor taken along line 14—14 of FIG. 3, and viewed in the direction of the arrows associated with said line.

40 FIGS. 15A, 15B, 15C, 15D and 15E are fragmentary longitudinal sections through the carton supply conveyor 45 illustrating different operational positions of the carton impelling and retaining components thereof.

FIG. 16 is an elevational detail view partly in section of a clutch that is interposed in the power train of the carton supply conveyor.

50 FIG. 17 is an exploded fragmentary perspective of the clutch illustrated in FIGURE 16.

FIG. 18 is a side elevational detail view of component mechanisms of said clutch.

FIG. 19 is a fragmentary perspective illustrating a 55 portion of the egg supply conveyor for the egg packing machine.

FIG. 20 is a fragmentary perspective detail view illustrating one of the egg supporting buckets of the egg supply conveyor shown in FIG. 19.

60 FIG. 21 is a perspective view of control mechanism, which operates to release eggs from the buckets of the egg supply conveyor as they pass over a carton underneath.

FIG. 22 is a plan view partly in section of the control 65 mechanism illustrated in FIG. 21.

FIG. 23 is a fragmentary side elevational detail view, partly in section, of one of the components of the control mechanism illustrated in FIGS. 21 and 22.

FIGS. 24A, 24B, 24C, 24D, 24E, 24F, 24G and 24H 70 are schematic plan views of the control mechanism illustrated in FIGS. 21 and 22 showing a sequence of consecutive operational positions thereof.

FIG. 25 is the electric circuit diagram of the egg packing machine of the invention.

FIGS. 26A, 26B, 26C, 26D, 26E and 26F are fragmentary schematic perspectives of the egg packing machine illustrated in FIG. 1, showing a sequence of different operational positions thereof.

General construction of the machine

The egg packing machine of the invention comprises a horizontally extending continuously advancing conveyor 100 that carries the eggs to be packed in a single file line to the actual packing station (FIGS. 1, 3 and 26A, to 26F). It also comprises an intermittently operating carton supply conveyor 102 that extends below and at right angles to the egg supply conveyor at the actual packing station, and a carton magazine 104 that is disposed above said carton supply conveyor at a point in front of the egg supply conveyor and which is adapted to receive a stack of cartons and is operable to drop them onto the carton supply conveyor 102 for conveyance thereon into egg receiving position below the egg supply conveyor 100. With the aid of a control mechanism 105 the operation of the three component mechanisms 100, 102 and 104 is regulated in such a manner that above a carton placed upon carton supply conveyor 102 with its leading pocket row in egg receiving position relative to egg supply conveyor 100, said egg supply conveyor drops a number of eggs equal to the number of pockets comprised in each pocket row of the carton at points displaced in a direction longitudinally of the egg supply conveyor advance by a distance equal to the distance between the center points of the pockets in each pocket row, commencing on the downstream side of the carton (considered with regard to the advance of the egg supply conveyor). Thereupon the carton supply conveyor 102 is actuated to advance at a relatively slow rate of speed by a distance effective to place the directly succeeding pocket row of the carton into egg receiving position below the egg supply conveyor, and the magazine 104 is actuated to drop an individual carton onto the carton supply conveyor 102. Then, the egg supply conveyor 100 is again caused to drop a number of eggs equal to the number of pockets comprised in each pocket row at longitudinally spaced points of its advance. Thereafter the carton supply conveyor 102 is actuated to advance at a relatively fast rate over the relatively long distance which places the first pocket row of a directly succeeding carton into egg receiving position below the egg supply conveyor 100.

The carton supply conveyor

The carton supply conveyor 102 comprises an endless sprocket chain 106 trained around a trailing sprocket 108 and a leading sprocket 110 (FIG. 3). The trailing sprocket 108 is the drive sprocket of the conveyor, and is firmly mounted on a transverse shaft 112 that extends with its opposite ends through a pair of vertically disposed, transversely spaced, elongated side panels 114a and 114b, which form part of the conveyor frame 115 (FIGS. 1, 2 and 3). The bottom edges of said side panels are turned inwardly to form base flanges 116a and 116b, respectively (FIG. 2), that may be rigidly connected by a cross bar 117 (FIG. 3) to impart sturdiness to the structure. The top edges of the panels 114a and 114b are bent outwardly to form flanges 118a and 118b, respectively (FIG. 11) to which are bolted at points rearwardly of the magazine longitudinally extending, elongated spring bars 119a and 119b that support the egg cartons as they are advanced by the conveyor 102. The leading sprocket 110 (FIG. 3) is an idler sprocket and is rotatably mounted upon a transverse shaft 120 which is firmly supported in the side panels 114a and 114b of the conveyor frame. Suitably supported from the conveyor frame 115 above the upper run 122 of the chain 106 is a longitudinally extending

elongated bar 124 that serves the double purpose of retaining the horizontal run of the conveyor chain in position, and of providing center support for the cartons after they have been advanced beyond the spring bars 119a and 119b (FIG. 3).

Supported from the chain 106 at longitudinally spaced points thereof are pairs of pusher plates 126a and 126b which are adapted to engage the trailing wall of a carton deposited upon the bars 119a and 119b, and slide the carton along said bars. For this purpose the chain 106 carries firmly secured thereto at equi-spaced points of its periphery cross rods 128 (FIGS. 11 and 12). Rotatably engaged over the laterally projecting rod portions 128a and 128b are sleeves 132a and 132b, respectively, that are rigidly secured to the lower ends of the pusher plates. Along the bottom run of the conveyor chain 106 the pusher plates are yieldably held in an ineffective rearwardly inclined position, as shown in FIG. 3, but as they reach, and travel along, the upper run of said chain 20 and pass underneath and beyond the magazine 104, means enter into operation that place them into a substantially steeper position approximately parallel to the somewhat reclining rear walls of the cartons deposited upon the conveyor 102 so that they may broadly engage the rear 25 wall of the cartons and thus act effectively as impellers. Having reference to FIGS 3, 12 and 14, springs 134a and 134b coiled around the laterally projecting rod portions 128a and 128b, respectively, with their opposite ends engaged behind shelves 136 that are rigidly secured to 30 said rod portions, and angle bars 138 that are rigidly secured to the pusher plates at the trailing surfaces thereof, urge said plates in a counterclockwise direction as viewed in FIG. 12 until the inwardly projecting end portions 140 of said angle bars 138 strike against the shelves 35 136, as shown in FIG. 15A. Under these conditions the pusher plates assume an acute angle position with regard to the endless sprocket chain 106 as they travel along the lower run thereof as shown in FIG. 3. As the pusher plates 126a and 126b climb onto the upper horizontal 40 run of the conveyor chain, however, rearwardly bent tail members 142 that are rigidly secured to and project downwardly from the sleeves 132a and 132b, respectively, come against horizontal camming bars 144a and 144b (FIGS. 11 and 12) that are supported from the side 45 panels 114a and 114b of the conveyor frame at either side, and at a level somewhat below the level, of the upper run 122 of the conveyor chain. Engagement of the tail members 142 with the bars 144a and 144b is effective to swing the pusher plates 126a and 126b in 50 clockwise direction as viewed in FIG. 12 from the position illustrated in FIG. 15A to the position illustrated in FIG. 15B. The camming bars 144a and 144b have a short initial portion 146 of somewhat lower level than the remaining portion 148 thereof (FIGS. 3 and 15B) and said lower level portion 146 terminates a short 55 distance before the rear wall of the carton magazine, as best shown in FIG. 3. When the tail members 142 of the two pusher plates engage the lower level portions 146 of the camming bars 144a and 144b, said pusher plates assume a position parallel to and slightly spaced from the rear wall of a carton on the supporting bars 119a and 119b so that the pusher plates cannot interfere with the descent of a carton from the magazine 104 into its proper position on the carton supply conveyor (FIGS. 60 15B and 15C). It is only after the pusher plates advance 65 from the described carton receiving position, that their tail members 142 climb onto and ride along the higher level portions 148 of their respective camming bars which causes the pusher plates to assume a steeper position 70 wherein their upper portions come into contact with the rear wall of the carton (FIG. 15D), and as said tail members climb on and slide along the higher level portions of the camming bars 144a and 144b, respectively, rollers 145a and 145b on the opposite ends of the transverse rods 128 make also contact with and roll along the 75

higher level portions of said bars, so that proper support is provided for the upper run of the conveyor chain in those regions where it is called upon to advance the weight of a carton before and after it has been filled with eggs.

Supported from the conveyor chain 106 an appropriate distance in advance of each pair of pusher plates are pairs of clamps 150a and 150b of symmetrically identical construction (FIGS. 3, 12 and 13). While travelling ineffectively along the lower run of the conveyor chain, said clamps are yieldably held in a rearwardly inclined position similar to the ineffective position assumed by the pusher plates as illustrated in FIGS. 3 and 15A. When they move underneath the carton magazine, however, and reach a position approximately in vertical alignment with the front wall of said magazine, they are turned into a more upright position wherein they permit a carton to drop from the magazine into the space between themselves and the trailing pair of pusher plates. After a carton has dropped into said space, and before the conveyor resumes operation to advance said carton into egg receiving position underneath the egg supply conveyor, the clamps 150a and 150b are tripped to clamp down upon the front wall of the carton, to hold it securely on the supporting bars 119a and 119b of the conveyor (FIG. 15C).

Having reference to FIGS. 3, 12, 13 and 15A, the endless conveyor chain 106 carries at points a suitable distance in advance of each pair of pusher plates a transverse rod 152 the opposite ends of which are provided with rollers 154a and 154b that ride upon the hereinbefore described camming bars 144a and 144b when they move along the upper horizontal run of the conveyor. Rotatably supported upon the laterally projecting portions 152a and 152b of said rods 152 are sleeves 156a and 156b, respectively, to which are rigidly secured the lower ends of the carton retaining clamps. Each of said clamps has the form of a plate whose upper edge is centrally recessed to form two transversely spaced fingers 158 and 160 (FIG. 13). Said fingers are bent upwardly as viewed in FIGS. 12 and 15B, but their tips are bent sharply in a direction toward their respective pusher plates i.e. in the direction opposite to the direction of movement of the conveyor, to form gripping hooks 162 and 164. Springs 166a and 166b coiled around the laterally projecting rod portions 152a and 152b, respectively, with their ends engaged behind shelves 168 that are rigidly secured to said rod portions, and angle bars 170 that are rigidly secured to the clamp plates at their trailing surfaces, urge said clamps in counterclockwise direction as viewed in FIG. 12, until the angle bars 170 strike against the hereinbefore mentioned shelves 168, as illustrated in FIG. 15A. In this position the clamps form an acute angle with respect to the conveyor chain as they travel along the lower run thereof as best shown in FIG. 3. However, when a pair of clamps approaches the hereinbefore mentioned position substantially in vertical alignment with the front wall of the magazine, rearwardly bent tail members 172 that are rigidly secured to and project downwardly from the sleeves 156a and 156b, respectively, come against a camming board 174 that is supported upon a transverse shaft 176 which is suitably journaled in the side panels 114a and 114b of the conveyor frame. Normally said board is held in a slightly upwardly slanting position, as illustrated in FIG. 15B, and as the tail members 172a and 172b of a pair of clamps come into contact with and ascend the upper surface of said board, the clamps are swung in clockwise direction from the idle position illustrated in FIG. 15A into the cocked position illustrated in FIG. 15B wherein they are spaced sufficiently far from their co-operating pusher members 126a, 126b to freely receive therebetween a carton released from the magazine. After a carton has been dropped into the pocket formed between a pair of pusher plates and a pair of clamps in cocked

position, the board 174 is swung in a clockwise direction as viewed in FIG. 15B into the position illustrated in FIG. 15C and releases the tail members 172. As a result thereof, the clamps swing in counterclockwise direction under the urgency of their respective springs 166a and 166b, and their gripping tips 162 and 164 snap over the upper edge of the leading carton wall, as illustrated in FIGS. 12 and 15C.

To operate the carton supply conveyor, rotary power from a motor (not shown) which operates continuously during the performance of the machine is applied to a sprocket 178 (FIG. 1). Said sprocket is firmly mounted upon a sleeve 179 which is suitably journaled in a panel 180b that is disposed exteriorly adjacent the hereinbefore described side panel 114b of the conveyor frame at the rear end thereof and within which is rotatably mounted one end of the hereinbefore mentioned conveyor drive shaft 112 (FIGS. 2 and 16). Rotatably received within said sleeve is one end of a transverse shaft 182 whose opposite end is suitably journaled in another panel 180a that is disposed exteriorly adjacent the rear end of the previously mentioned side panel 114a of the conveyor frame and within which is rotatably mounted the opposite end of the conveyor drive shaft 112. The panels 180a and 180b have inwardly turned bottom flanges 184a and 184b, respectively (FIG. 2) which may be connected by suitable cross channels 186 and 188 (FIG. 3). The transverse shaft 182 is operatively connected to the hereinbefore mentioned drive shaft 112 of the conveyor by a transmission 189 to be presently described in greater detail.

Interposed between the sleeve 179 and the transverse shaft 182 is a clutch 190 that is normally held in disengaged position so that the transverse shaft 182 remains at rest, and which is engaged for revolution through an angle of 180° whenever it is necessary to advance the carton supply conveyor so as to place an empty pocket row of a carton on said conveyor into egg receiving position relative to the egg supply conveyor 100.

Having reference to FIGS. 16 and 17, the sleeve 179 forms a radially enlarged head 192 around which is wound a coil spring 194. The trailing end of said spring (viewed in the direction of rotation of sleeve 179) is anchored in a disc 196 that is firmly mounted upon the transverse shaft 182, while its leading end is anchored in a ratchet 198 that is rotatably supported upon the sleeve 179 by means of a ball bearing 200. Normally the ratchet 198 is held against rotation by means of a latching pawl 202 that is rotatably mounted upon a stub shaft 204 (FIG. 18) which projects inwardly from the inner surface of the rear panel 180b, the nose 206 of said pawl being forced into engagement behind one of the teeth of the ratchet 198 by means of a spring 208 (FIG. 18). As long as the leading end of the hereinbefore mentioned spring 194 around sleeve head 192 is positively restrained from movement in the direction of rotation of sleeve 179 by its connection with the ratchet 198 in latched position, while frictional engagement of said spring 194 with the head 192 of rotating sleeve 179 endeavors to impart rotation to said spring, the spring 194 is subjected to an unwinding stress which increases its diameter so that its convolutions lose contact with the head 192 of rotating sleeve 179. As a result thereof the sleeve 179 idles ineffectively within the spring 194, and the transverse shaft 182 remains at rest. However, when the pawl 202 is disengaged from the ratchet 198, the clutch spring 194 may contract to its normal diameter, and grip the head 192 of sleeve 179; and as the spring 194 tends to turn with the sleeve, while its trailing end is held back by the inertia of the conveyor mechanism in whose disc 196 it is anchored as explained hereinbefore, said spring 194 is subjected to a winding stress which reduces its diameter so that it clutches firmly the head 192 of rotating sleeve 179, and participates fully in the rotary movement thereof of forcing the transverse shaft 182 to follow suit. When

rotation of the ratchet 198 is blocked by re-engagement of the pawl 202 with another one of the ratchet teeth, the spring 194 is again subjected to an unwinding stress which interrupts the driving connection between the sleeve 179 and the clutch shaft 182 and rotation of the transverse shaft 182 comes to a halt.

To prevent that the conveyor 102—which is driven from transverse shaft 182 as mentioned hereinbefore—overshoots its mark under its inertia, the disc 196 is provided with an adjustable stop member 197 that is arranged to strike against a stop ledge 199 which is rigidly secured to and projects laterally from the ratchet 198 as shown in FIGS. 16 and 17.

To disengage the pawl 202 from the ratchet 198 for the purpose of allowing the carton supply conveyor 102 to advance, a solenoid 210 (FIGS. 2 and 18) is arranged below said pawl 202. The normally projected armature 212 of said solenoid 210 is pivotally connected through a link 214 to the free end of pawl 202. Thus, whenever the solenoid 210 is energized and retracts its armature 212, it withdraws the nose of the pawl 202 from the ratchet 198 causing engagement of the clutch 190 in the manner described hereinbefore. The peripheral edge of the ratchet 198 possesses two teeth 216a and 216b respectively, corresponding to the two conveyor advances that are necessary to place the two pocket rows of a carton of the type illustrated in FIGS. 15B, 15C, 15D and 26A to 26F successively into egg receiving position below the egg supply conveyor. Energization of the pawl retracting solenoid 210 is controlled from the hereinbefore mentioned central control mechanism 105 that governs the release of eggs from the egg supply conveyor 100 as well as the advance of the carton supply conveyor in a manner to be described in greater detail hereinafter.

To enable two consecutive half revolutions of the clutch shaft 182 to drive the conveyor 102 alternately at higher and lower speeds, respectively, over the larger distance necessary to place the first pocket row of a new carton underneath the egg supply conveyor 100, and the shorter distance necessary to place the second pocket row of the same carton underneath the egg supply conveyor, another transverse shaft 220 (FIGS. 3, 7, and 8) rotatably mounted in the rear panels 180a and 180b of the conveyor frame is disposed intermediately of the clutch shaft 182 and the conveyor drive shaft 112, and firmly mounted upon said intermediate shaft 220 is a gear 222 that meshes with another gear 224 which is firmly mounted upon the clutch shaft 182. Secured to said intermediate shaft 220 is a mutilated gear 226 of larger diameter than gear 222, and the toothed segment 228 of said mutilated gear is arranged to mesh intermittently with the toothed segment 230 of another mutilated gear 232 of substantially smaller diameter that is firmly mounted upon the conveyor drive shaft 112. The number of teeth comprised in the toothed segment 228 of the large diameter mutilated gear 226 is equal to the number of teeth comprised in the toothed segment 230 of the small diameter mutilated gear 232, and the number of teeth comprised in said last mentioned segment is so chosen that the teeth extend over an arc corresponding to the rotation of conveyor drive shaft 112 necessary to move a carton from underneath the magazine 104 (FIG. 9A) into a position wherein its first pocket row is disposed vertically below the egg supply conveyor 100 (FIG. 9B). Rigidly secured to the mutilated gear 226 on intermediate shaft 220 by pins 233 is another mutilated gear 234 which is of smaller diameter than the mutilated gear 226. The toothed segment 236 of said mutilated gear 234 of smaller diameter is located in a sector opposite to the toothed segment 228 of the mutilated gear 226 of larger diameter, and is arranged to mesh intermittently with the toothed segment 238 of yet another mutilated gear 240 that is mounted upon the conveyor drive shaft 112 adjacent the mutilated gear 232 and is rigidly connected to said last mentioned gear for rotation in unison by suitable pins 242, and which

is of larger diameter than the juxtaposed mutilated gear 232. The number of teeth comprised in the toothed segment 236 of the mutilated gear 234 on intermediate shaft 220 is equal to the number of teeth comprised in the toothed segment 238 of mutilated gear 240 on the conveyor drive shaft 112, and the number of teeth in said last mentioned toothed segment 238 is so chosen that they extend over an arc corresponding to the rotation of conveyor drive shaft 112 necessary to move the second pocket row of a carton on the conveyor into egg receiving position below the egg supply conveyor 100 (FIG. 9D). At the same time the rotary position of the mutilated gear 240 on conveyor drive shaft 112 is such and the diametrical size of said mutilated gear 240 is so chosen that its toothed segment 238 is located in the angular interval left between the ends of the toothed segment 230 of the smaller mutilated gear 232 on conveyor drive shaft 112, as best shown in FIGS. 7 and 8.

The rotary position of the cooperating mutilated gears 20 on conveyor drive shaft 112 and intermediate shaft 220 respectively is so chosen with regard to the ratchet 198 on sleeve 179 that when the first tooth 216a of said ratchet is engaged by the pawl 202, the toothed segments 228 and 230 of mutilated gears 226 and 232, respectively, are 25 about to engage each other as illustrated in FIGS. 7 and 9A. Hence, when the initially mentioned control mechanism 105 causes disengagement of the latching pawl 202 from said ratchet tooth 216a and the clutch shaft 182 commences to rotate, the toothed segment 228 of the 30 large diameter mutilated gear 226 on intermediate shaft 220 engages the toothed segment 230 of the small diameter mutilated gear 232 on conveyor drive shaft 112 and turns said drive shaft through the angle necessary to cause advancement of a carton from underneath the magazine 35 104 to a position where its leading pocket row is disposed vertically below the egg supply conveyor (FIG. 9B); and due to the fact that the diameter of the drive gear 226 is large compared with the diameter of the driven gear 232, the rate of advance of the conveyor during the described phase in its operation is relatively rapid. When the clutch shaft 182 has completed a half revolution and comes to a halt with the latching pawl 202 engaged behind the second tooth 216b of ratchet 198, the described transmission is in the position illustrated in FIGS. 8 and 40 45 9C, wherein the segment 236 of the small diameter mutilated gear 234 on intermediate shaft 220 is about to engage the toothed segment 238 of the large diameter mutilated gear 240 on conveyor drive shaft 112. Hence, when the control mechanism 105 causes withdrawal of the latching pawl 202 from the second tooth 216b of the 50 55 ratchet 198 and the clutch shaft 182 performs another half revolution, the toothed segment 236 of the mutilated gear 234 on the intermediate shaft 220 engages the toothed segment 238 of the mutilated gear 240 on conveyor drive shaft 112, and turns the conveyor drive shaft through the angle necessary to move the second pocket row of the carton on the conveyor into a position vertically below the egg supply conveyor (FIG. 9D); and since the diameter of the driving gear 234 is only slightly larger than 60 65 the diameter of the driven gear 240, the rate of advance of the conveyor during this second phase in its operation is relatively slow so that eggs deposited into the first pocket row of the carton will not be jarred and will not jump out of the carton.

To limit the operation of the carton supply conveyor 102 to exactly the advances necessary to place the consecutive pocket rows of cartons travelling thereon successively into egg receiving position below the egg supply conveyor, the cooperating mutilated gears of the described 70 75 transmission arrangement 189 are constructed with coacting locking cams and locking recesses, respectively, in the manner of Geneva gears. Having again reference to FIGS. 7, 8, and 9 the edge of the large diameter drive gear 226 on intermediate shaft 220 forms directly behind its toothed segment 228 a first locking cam 244 that is

arranged to engage a concave recess 246 formed in the edge of the small diameter driven gear 232 directly behind the toothed segment 230 thereof (FIG. 9B). In angular alignment with the toothed segment 236 of the small diameter drive gear 234, however, the edge of the large diameter drive gear 226 forms a recess 248 to permit rotation of the driven gear unit 232/240 during engagement of the toothed segment 236 of the small diameter drive gear 234 with the toothed segment 238 of the large diameter driven gear 240 (FIG. 9C) and directly thereafter the edge of the larger diameter drive gear 226 forms another locking cam 250 that is adapted to engage a concave recess 252 formed in the edge of the small diameter driven gear 232 adjacent the leading end of its toothed segment 230 (FIG. 9D). Similarly the edge of the small diameter drive gear 234 forms directly behind its toothed segment 236 a first locking cam 254 that is adapted to engage a concave recess 256 formed in the edge of the large diameter driven gear 240 adjacent the trailing end of its toothed segment 238 (FIG. 9A); and in angular alignment with the toothed segment 228 of the large diameter drive gear 226 the edge of the small diameter drive gear 234 forms a recess 258 to permit rotation of the driven gear unit 232/240 during engagement of the toothed segment 228 of the large diameter drive gear 226 with the toothed segment 230 of the small diameter drive gear 232. Directly thereafter the edge of the small diameter drive gear 234 forms a second locking cam 260 that is adapted to engage a concave recess 262 in the edge of the large diameter driven gear 240 adjacent the leading end of its toothed segment 238 (FIG. 9B).

The magazine

Disposed above the carton supply conveyor 102 is the magazine 104 (FIGS. 1 and 3) which is of a rectangular horizontal cross-section, and is of a size appropriate to receive a stack of vertically superposed cartons. The magazine 104 is formed by two vertically disposed, transversely spaced channels 280a and 280b of U-shaped cross section that face each other with their open sides. The front flanges 282a and 282b of said channels 280a and 280b are rigidly connected near their upper and lower ends by cross rods 284 and 286 to impart sturdiness to the structure, and the upper corners 288a and 288b of the rear flanges 290a and 290b, respectively, of said channels are twisted outwardly to form funnelling surfaces, as shown in FIGS. 1 and 2, to facilitate insertion of a stack of superposed cartons into the magazine. At their lower ends the channels 280a and 280b are welded to rectangular mounting plates 292a and 292b, respectively, which are rigidly supported from, and exteriorly of, the side panels 114a and 114b of the conveyor frame by a number of bolts 294 (FIGS. 11, 13 and 14). The lower ends of the front flanges 282a and 282b of the magazine channels are cut away up to a level sufficiently high above the conveyor 102 to allow a carton deposited onto said conveyor to emerge freely from the magazine as shown in FIG. 3.

The carton dispensing mechanism

The lower ends of the eight portions 296a and 296b of the U-channels 280a and 280b are provided with centrally located vertical slots 298a and 298b, respectively, as shown in FIGS. 1, 3 and 11. Through said slots reach fingers 300a and 300b that normally support a stack of superposed cartons above the conveyor with their unfolded lids in contact with the rear flanges of the magazine channels by engaging the wedge-shaped recess 302 in the floor 304 of the lowest carton in the stack, as illustrated in FIGS. 3, 26A, 26D and 26E. During operation of the machine the fingers 300a and 300b operate to deposit the cartons individually onto the supporting bars 119a and 119b of the conveyor 102. For this purpose the fingers 300a and 300b are initially located in the upper ends of the vertical slots 298a and 298b at a level

sufficiently high above the conveyor 102 to allow said conveyor to withdraw a previously deposited carton with its lid in a steeply reclined position from underneath the stack of cartons that is supported by the fingers 300a and 300b (FIG. 26A), and as soon as another carton is needed means enter into operation that withdraw the fingers 300a and 300b outwardly from underneath the carton stack allowing the total stack to drop onto the supporting bars of the conveyor which is at a standstill at the moment, with a pair of its pusher plates 126a and 126b in rearwardly inclined position located a limited distance in front of the rear flanges 290a and 290b of the magazine channels, and a pair of clamps 150a and 150b located in cocked position below the front flanges 282a and 282b of the magazine channels as illustrated in FIG. 26B. To guide the stack of cartons dependably into the pocket formed by and between the pusher plates and the clamps below the front and rear walls, respectively, of the magazine rearwardly bent arcuate guide bars 306a and 306b are secured to, and rise from, the elongated spring bars 119a and 119b of the conveyor at points in vertical alignment with the rear flanges of the magazine channels as best shown in FIG. 11.

As the stack-supporting fingers 300a and 300b are laterally withdrawn from the magazine, they are also lowered until they are positioned opposite the ends of the wedge-shaped recess 302 in the floor of the second lowest carton in the magazine as likewise shown in FIG. 26B. Then, as the operation proceeds and while the conveyor is still at rest, the fingers 300a and 300b are again projected into the magazine, and are then raised to their initial level so that they left the remaining stack in the magazine sufficiently high above the lowermost carton, which remained upon the conveyor bars 119a and 119b, for said lowermost carton to be readily withdrawn from underneath the stack as soon as the conveyor commences operation (FIGS. 26D and 26E). To avoid that during this phase in the operation of the carton dispensing mechanism the stack of cartons may force the raised lid of the lowermost carton against the rear flanges of the magazine channels, and in this manner grip said lid and lift said lowermost carton above the conveyor, the lower ends of said rear flanges 290a and 290b are removed up to a level slightly above the top edge of the raised lid of a carton resting upon the supporting bars 119a and 119b of the conveyor as shown in FIGS. 3 and 11. Also, before the stack in the magazine is raised as described, the clamps 150a and 150b underneath the front flanges of the magazine channels are tripped and engage the edge of the leading wall of the lowermost carton as illustrated in FIG. 26D to positively retain the carton on the conveyor 102 as the remaining stack is elevated within the magazine. Thereafter, the conveyor 102 commences operation to remove the gripped carton from underneath the stack of cartons in the magazine, the first effect of its advance being to steepen the position of the pusher plates 126a and 126b behind the carton until their upper portions engage the rear wall of the carton, as previously described. Thereafter the carton is fully withdrawn from the magazine and its leading pocket row is placed into egg receiving position below the egg supply conveyor 100 (FIG. 26E); then after said pocket row has been filled with eggs, and the conveyor has again advanced to place the second pocket row of the carton into egg receiving position, the fingers 300a and 300b are again withdrawn from underneath the stack of cartons in the magazine permitting it to drop upon the conveyor between a pair of reclined pusher members and a pair of cocked retaining clamps which have meanwhile moved into their proper positions below the magazine as illustrated in FIG. 26F.

The described operation of the carton dispensing fingers is controlled from cams 308 and 310 that are firmly mounted upon, and turn with, the hereinabove described transverse clutch shaft 182. Having reference to FIGS.

5 and 12, the fingers 300a and 300b are secured to the ends of two arms 312a and 312b, respectively, that extend parallel to and exteriorly of the repeatedly mentioned rear panels 180a and 180b of the conveyor frame (FIG. 1). The opposite ends of said arms are rigidly secured to C-shaped brackets 314a and 314b, respectively, that mount vertically disposed hinge rods 316. Said hinge rods are rotatably received in blocks 318a and 318b, which are firmly mounted upon the opposite ends of a transverse shaft 320 that is rotatably supported in the rear panels 180a and 180b of the conveyor frame rearwardly of the clutch shaft 182 as shown in FIGS. 2 and 12. Firmly secured to said clutch shaft 182 is the cam 308 as pointed out hereinabove, and the edge of said cam is engaged by a roller 322 which is pivoted to the end of an arm 324 that projects forwardly from yet another transverse shaft 326 which is rotatably supported in the rear panels 180a and 180b intermediately of the hereinbefore mentioned shaft 320 and clutch shaft 182. A spring 328 tensioned between the end of another arm 330 that is rigidly secured to the shaft 326 and the cross bar 188 of the conveyor frame holds the roller 322 in engagement with the edge of cam 308, as best shown in FIG. 4. Rigidly secured to the shaft 326 near the opposite ends thereof are bars 332a and 332b whose free ends engage inwardly slanting surfaces 334a and 334b, respectively, formed by blocks 336a and 336b of inverted triangular conformation that are rigidly secured to the inner surfaces of the finger-supporting arms 312a and 312b at points intermediately of fingers 300a, 300b and the hinge rods 316. As long as the cam 308 presents a sector 338 of reduced radius to the roller 322 on arm 324 (FIG. 4), the bars 332a and 332b on shaft 326 are in the downwardly slanting position illustrated in FIG. 12 wherein their ends are disposed below the tapering ends of the blocks 336a and 336b. Under such conditions a spring 340 tensioned between the finger-supporting arms 312a and 312b holds said arms in a position substantially parallel with the rear panels 180a and 180b of the conveyor frame wherein the fingers 300a and 300b are projected into the interior of the magazine (FIG. 26A). Adjoining its sector 338 the cam 308 forms first a shallow rise 342 and then a steep rise 344. When during rotation of the clutch shaft 182 the cam 308 presents its shallow rise 342 to roller 322, the shaft 326 is swung in a counterclockwise direction as viewed in FIG. 12 which lifts the camming bars 332a and 332b into contact with the tapering end of the triangular blocks 336a and 336b on the finger supporting arms 312a and 312b, respectively. Then, as further rotation of the clutch shaft 182 forces the roller 322 to climb the steep rise 344 of cam 308, the shaft 326 is abruptly swung still further in counterclockwise direction which raises the bars 332a and 332b along the inwardly slanting surfaces 334a and 334b of the triangular blocks 336a and 336b, respectively. This forces the arms 312a and 312b to swing outwardly on their hinge rods 316 against the urgency of spring 340, and as a result thereof the stack supporting fingers 300a and 300b are withdrawn from the magazine and allow the stack of cartons within the magazine to drop onto the conveyor bars 119a and 119b (FIG. 26B).

To effect downward movement of the withdrawn fingers 300a and 300b so that they may move underneath the second lowest carton in the stack, the hereinbefore mentioned cam 310 on clutch shaft 182 is engaged by a roller 346 that is pivoted to the free end of an arm 348 which is firmly mounted upon, and projects forwardly from, the hereinbefore mentioned transverse shaft 320. Springs 350a and 350b tensioned between the arms 312a and 312b, respectively, and lugs 351a and 351b provided on the outer surfaces of the rear panels 180a and 180b (FIGS. 1, 4 and 5) hold the roller 346 in engagement with the contour of the cam 310. Whenever the cam 310 presents a sector 352 of increased radius to the roller 346, it holds the shaft 320 in the counterclockwise posi-

tion illustrated in FIGS. 5, 12 and 26A, wherein the stack supporting fingers 300a and 300b are positioned near the upper ends of the slots 298a and 298b in the magazine sidewalls, and the stack of cartons supported by said fingers is raised sufficiently high above the conveyor to allow a carton on said conveyor to emerge freely from underneath said stack. During rotation of clutch shaft 182, however, the cam 310 presents a sector 354 of reduced radius to the roller 346, which enables the springs 350a and 350b to lower the arms 312a and 312b to the position illustrated in FIGS. 26B and 26C; and since the finger-withdrawing rise 344 of cam 308 and the finger-lowering recess 354 of cam 310 are arranged to act upon their respective cam follower rollers 322 and 346 simultaneously, as apparent from a comparison of FIGS. 4 and 5, the same rotary increment of clutch shaft 182 effects withdrawal and downward movement of the stack supporting fingers 300a and 300b from the position illustrated in FIG. 26A to the position illustrated in FIG. 26B.

The rise 344 of cam 308 is a much shorter duration than the recess 354 of cam 310, and as a result thereof the spring 340 will return the fingers 300a and 300b to their inwardly projected positions while they are still at the level determined by the recess 354 in cam 310. Hence, the fingers 300a and 300b are moved underneath the second lowest carton in the carton stack within the magazine as illustrated in FIG. 26C. At the same time a third cam 356 that is likewise secured to the clutch shaft 182, is arranged to trip the hereinbefore mentioned camming board 174 for the carton retaining clamps 150a and 150b below the front flanges of the magazine channels causing said clamps to engage the upper edge of the front wall of the carton on conveyor 102.

Having reference to FIGS. 6 and 12, the edge of said cam 356 is engaged by a roller 358 that is pivoted to the end of an arm 360. Said arm is firmly mounted upon another transverse shaft 362 that is journaled in the rear panels 180a and 180b of the conveyor frame near the bottom flanges 184a and 184b thereof. A spring 364 tensioned between arm 360 and a cross brace 366 which connects the upper edges of panels 180a and 180b, maintains the roller 358 in engagement with the edge of cam 356. The shaft 362 carries also an upwardly directed arm 368 that is pivotally connected to one end of an elongated forwardly extending link 370. The opposite end of said link is pivoted to the free end of an arm 372 that is firmly secured to and extends downwardly from the hereinbefore mentioned shaft 176 which carries the camming board for the carton retaining clamps 150a and 150b.

The contour of cam 356 is divided into a major portion 374 of reduced diameter and a minor portion 376 of increased diameter, and while the above described stack releasing operations occur, the cam 356 presents its sector 374 of reduced diameter to its roller 358 enabling the spring 364 to hold the camming board 174 in the upwardly slanted position illustrated in FIG. 15B wherein said board will cam an approaching pair of clamps 150a and 150b into the cocked position shown in said FIG. 15B and in FIGS. 26A, 26B and 26F. Thereafter, when further rotation of the clutch shaft 182 projects the stack supporting fingers at the lower level of their vertical travel into stack supporting position wherein they move in below the second lowest carton in the magazine, and before said fingers are raised to their initial level to lift the remaining stack of cartons above the lowermost carton on conveyor 102, the cam 356 presents its sector 376 of increased radius to its roller 358 as shown in FIGS. 6 and 26D. This causes arm 360 to swing in counterclockwise direction as viewed in FIG. 6, pulling the link 370 to the left, with the result that the camming board 174 assumes the downwardly slanting position illustrated in FIGS. 6 and 15C instead of the upwardly slanted position shown in FIG. 15B. In consequence thereof the tails 172a and 172b of the clamps 150a and 150b

lose contact with the board 174 permitting the springs 166a and 166b to swing the clamps in counterclockwise direction from the position illustrated in FIG. 15B to the position illustrated in FIG. 15C wherein they engage over the front edge of the carton body and hold the carton securely on the conveyor. It is only then that the cam 310 presents its sector 352 of increased diameter to its roller 346 which forces the arms 312a and 312b to swing upwardly against the urgency of springs 350a and 350b causing the fingers 300a and 300b to disengage the remaining stack of cartons from the lowermost carton and to lift said stack to a level at which the conveyor may conveniently remove said lowermost carton from underneath said stack as illustrated in FIG. 26D.

During the directly succeeding 180° of revolution of the clutch shaft 182 which advances the conveyor by a distance effective to withdraw the lowermost carton from underneath the stack in the magazine, and places its leading pocket row into egg receiving position below the egg supply conveyor 100, the cam 310 maintains the arms 312a and 312b and hence the stack of cartons within the magazine in elevated position, while the cam 308 moves its initial rise 342 underneath its roller 322 which readies its power train for instantaneous withdrawal of the fingers 300a and 300b from the magazine at the beginning of the next operational phase of the clutch shaft 182.

The clamps 150a and 150b hold the cartons down upon the conveyor 102 until they approach the leading end of its upper run. Before they begin to descend about the idler sprocket 110 of the conveyor chain, their tail members 172 strike against camming blocks 380a and 380b (FIGS. 3, 14 and 15E). This forces the clamps in clockwise direction as viewed in FIG. 15D against the urgency of springs 166a and 166b into the position illustrated in FIG. 15E so that they release whatever carton they engaged during their travel along the horizontal run of the conveyor 102. The camming blocks 380a and 380b are secured to sleeves 382a and 382b that are engaged over the sprocket shaft 120 at either side of the sprocket 110. To hold the camming blocks in position, said sleeves form flat upper surfaces 384a and 384b respectively, that bear against abutments 386a and 386b provided on the underside of the hereinbefore described camming bars 144a and 144b near the leading ends thereof. The camming blocks 380a and 380b are of such conformation that they maintain the clamps in carton-releasing position until said clamps have dropped below the level of the upper conveyor run. Hence the pusher plates 126a and 126b may push the filled cartons without interference onto the take-off ramp 388 that is formed by the terminal portions of the panel flanges 118a and 118b and the center bar 124 (FIGS. 1 and 3).

Egg supply conveyor

The conveyor 100 that carries the eggs to be packed, over the hereinbefore described carton supply conveyor 102 for deposition into the pockets of a carton on said last mentioned conveyor 102, comprises a pair of parallel transversely spaced endless chains 410a and 410b (FIGS. 1, 3 and 19), the opposite ends of which are trained over suitable drive and idler sprockets (only the idler sprockets 411a and 411b being visible in FIGS. 1 and 3). Held between the chains 410a and 410b is an endless sequence of egg supporting buckets 412. Said buckets have the form of downwardly converging open ended shells that are adapted to receive and support eggs at their diverging upper ends, and which may be operated to drop said eggs through their lower ends at predetermined points along the upper run of the egg supply conveyor. For this purpose each of said buckets is formed by two segments in the form of semi-cylindrical shells 414 and 416 that face each other with their concave surfaces (FIG. 20). Adjacent their side edges, and near their upper ends, each of said shells is provided with outwardly directed tubular bosses 418a, 418b, and 420a, 420b, re-

spectively, within which are rotatably received transversely aligned elongated pivot pins 422a and 422b of the two parallel sprocket chains 410a and 410b, respectively. Intermediately each two consecutive buckets the parallel chains of the egg supply conveyor may be connected by cross rods 424, as shown. The bosses 418b and 420b on the right side of the bucket segments, as viewed in the direction of movement of the egg supply conveyor, carry firmly secured thereto enmeshed gear segments 426 and 428, respectively, and the leading gear segment 426 of each bucket forms an upwardly directed actuating nose 430 whose leading surface is rearwardly slanted as shown at 432. A suitable spring 434 tensioned between points of said segments 426 and 428 below the bosses 418b and 420b, respectively, urges the semi-cylindrical shells of each bucket into a closed position as illustrated in FIG. 20, wherein they properly support an egg delivered thereinto at the diverging upper end thereof.

Suitably supported from the front flanges 282a and 282b of the magazine channels 280a and 280b is a shelf 436 which carries a battery of six solenoids 440, one above each of the pockets in the vertically aligned pocket row of a carton on the carton supply conveyor underneath (FIGS. 1, 3 and 19). While these solenoids have above been collectively indicated by the reference numeral 440, they may hereinafter be individually identified by the reference numerals 441 to 446, respectively, wherever necessary in the following description of the operation of the egg packing machine for a clearer understanding of my invention.

Each of the solenoids 440 is arranged, upon energization, to project momentarily a ledge 448 into the path of the noses 430 on the segments 426 of predetermined egg supporting buckets 412 as they pass over the carton supply conveyor 102. As the rearwardly slanted leading edge 432 of a nose 430 on the segment 426 of a bucket 412 comes against such a ledge 448 in projected position, said segment 426 is forced to swing in clockwise direction as viewed in FIG. 20 against the urgency of spring 434. Clockwise movement of the leading segment 426 moves the trailing segment 428 which is enmeshed therewith in counterclockwise direction, and as a result thereof the lower ends of the two semi-cylindrical shells 414 and 416 are forced to swing apart, as illustrated at 450 in FIG. 19, and are therefore no longer capable of supporting an egg, so that any egg that may be seated in the bucket at the moment will drop through its opened lower end into the pocket of a carton underneath.

Since the egg supply conveyor 100 is continually in motion during operation of the machine, and moves relatively fast, an egg released from a bucket 412 does not drop from the bucket in a straight line but forms a parabolic trajectory. The position of the actuating ledges 448 relative to the corresponding pockets of a carton on the carton supply conveyor 102 should therefore be such that they engage the leading gear segments 426 of the buckets before the buckets reach a position in vertical alignment with the pockets presented to them by a carton on the carton supply conveyor underneath. Hence, the parabolic trajectory of an egg dropped from an advancing bucket 412 will lead it directly into its proper pocket. To cushion the impact of the eggs on the carton bottom, spacer strips 451 may be interposed between the spring bars 119a, 119b and their supporting flanges 118a, 118b respectively, as shown in FIGS. 3 and 11, and said strips may be arranged to terminate at points in front of the egg receiving position of a carton, while the free ends of the spring bars extend to points beyond the egg receiving position of the carton where they are bent to slant downwardly into loose supporting contact with the flanges 118a and 118b as shown at 452 in said FIGS. 3 and 11.

The control mechanism

To drop the eggs in proper order from the egg supply conveyor 100 into the pockets of a carton on the carton

supply conveyor 102, a mechanism that operates in synchronism with the advance of the egg supply conveyor, and which senses the presence of eggs in the buckets of said conveyor, causes energization of the bucket opening solenoids 440 in the proper sequence commencing with the solenoid 446 on the downstream side of the egg packing unit; and after six eggs have been dropped from the egg supply conveyor 100 into the six adjacent pockets of a pocket row in the carton on conveyor 102, said control mechanism which has hereinbefore been identified by the reference numeral 105 (FIGS. 1 and 3) causes brief energization of the previously described ratchet-release solenoid 210 to effect engagement of clutch 190 and permit the conveyor 102 to advance by a distance that will bring the directly succeeding pocket row of the carton, or the leading pocket row of a directly succeeding carton as the case may be, into egg receiving position below the egg supply conveyor 100, whereupon said control mechanism 105 operates again to energize the bucket opening solenoids 440 in their proper sequence to fill another pocket row with eggs.

As an egg on the egg supply conveyor 100 approaches the carton supply conveyor 102 and moves through a point a predetermined distance ahead of the downstream side of a carton on said conveyor—which distance is equal to the length of six consecutive buckets 412 in the exemplary embodiment of the invention that I am about to describe—it encounters a resilient sensing finger 454 (FIG. 19) that projects from above into the path of the upwardly protruding ends of the eggs in the buckets of the egg supply conveyor. Said sensing finger forms part of the actuating arm 456 of a normally open switch 458 which is suitably supported from the frame 460 of the egg supply conveyor 100, and which is briefly closed whenever an egg in a bucket 412 engages the sensing finger 454 and pushes it out of its path. Whenever the switch 458 is closed, it sets into motion mechanism that will release the egg which caused its closure from its supporting bucket 412 at the very moment when it travels over an empty pocket in the carton held underneath the egg supply conveyor 100 by the carton supply conveyor 102. If the carton pocket row in alignment with the egg supply conveyor is entirely empty, said mechanism is arranged to effect discharge of the egg from the egg supply conveyor into the pocket at the downstream end of said pocket row, and succeeding eggs on said egg supply conveyor 100 are successively dropped into the remaining five pockets in an upstream direction.

The control mechanism 105 is basically a memory device that operates in synchronism with the egg supply conveyor 100, and which comprises a vertical shaft 462 that may be rotatably supported from the hereinbefore mentioned shelf 436 by means of two vertically superposed brackets 464 and 466 (FIGS. 1 and 3). Supported from the vertical shaft for rotation therewith is a pair of vertically spaced mounting discs 468 of which only the upper one is visible in FIGS. 21 and 22. Said discs are provided with eight angularly equi-spaced, vertically aligned mounting slots 470 and received within, and secured to, angularly aligned ones of said slots are eight short, vertically disposed channels 472 of U-shaped cross-section whose open sides face in outward direction. Pivoted supported within each of said channels for rotation about a horizontal axis is a memory pin 474 which may be of steel, but is preferably made of nylon, and which projects with one of its ends beyond the periphery of the rotor 476 formed by the discs 468 and the channels 472. The rotation of each memory pin 474 about its horizontal pivot 478 is positively limited by studs 480 and 482 that are mounted within the side flanges of the channels 472 above and below the pins as shown in FIG. 21, and which determine the ineffective and the effective positions respectively of said pins.

Disposed below the circular row of pins 474 is a base plate 484 of horseshoe shape that embraces the rotor 476,

and which may be supported at its ends by two vertical rods 486a and 486b which are in turn supported from the hereinbefore mentioned vertically spaced brackets 464 and 466 (FIGS. 1 and 3).

Arranged along the inner edge of the horseshoe plate 484 for driving engagement by the memory pins 474 is a semi-circular row of six Geneva gears 491, 492, 493, 494, 495, and 496 (FIGS. 21 and 22). Said Geneva gears may be made of plastic material and each has six equi-spaced notches 497, corresponding to the six egg discharge effecting solenoids 440, which notches are adapted to be operatively engaged by the protruding ends of the memory pins 474 when said pins are in their effective positions. Each Geneva gear possesses a tubular stem 498 (FIG. 23) that turns upon a vertical stud 499 which rises from a common U-shaped mounting plate 500 that is adjustably supported upon the horseshoe plate 484. Arranged along the outer periphery of the semi-circle formed by the six Geneva gears are six switches 501, 502, 503, 504, 505 and 506, that lie in the individual power circuits (FIG. 25) of the six consecutive bucket release solenoids 441 to 446 disposed adjacent the egg supply conveyor 100 above the carton supply conveyor 102 (FIG. 19). The switches 501 to 506 are bolted to the U-shaped mounting plate 500, and their position is controlled by cams 508 formed on the stems 598 of the Geneva gears (FIG. 23) depending upon the rotary position of said gears. The edges of said cams 508 have each a solitary depression 510, as shown in FIGS. 22, and 24A to 24H, and as long as a roller 512 provided on the actuating arm 514 of each of said switches rides upon the circular contour 516 of its respective cam, the switch is held in open position, but when it drops into said depression 510 the switch will close.

During operation of the machine the rotor 476 formed by the discs 468 and the channels 472 turns in counter-clockwise direction as viewed in FIG. 22 in synchronism with the egg supply conveyor 100 such that at a given time interval the same number of memory pins 474 will pass a stationary point as do buckets 412 on the egg supply conveyor. For this purpose the lower end of the vertical shaft 462 may be provided with a bevel gear 518 of suitable size which meshes with another bevel gear 520 that is secured to the idler shaft 522 at the leading end of the egg supply conveyor and is driven from said conveyor (FIGS. 1 and 3).

During rotation of rotor 476 the memory pins 474 which project from the channels 472 sweep ineffectively above the Geneva gears 491 to 496, as long as they are in their upwardly tilted ineffective position as determined by engagement with the upper limit studs 480. Mounted upon the horseshoe plate 484, however, ahead of the first Geneva gear 491 is a solenoid 524 (FIGS. 21 and 22) that is energized by closure of the hereinbefore described egg sensing switch 458 (FIG. 25). The armature 526 of the solenoid 524 is shaped in the manner of a T, with its cross bar 528 positioned slightly above the level of the circular row of memory pins 474 as long as the solenoid 524 is in de-energized condition. Upon energization of the solenoid 524, however, which is indicative of the approach of an egg on the egg supply conveyor 100, the cross bar 528 of its armature 526 bears down upon a passing pin and shifts it into its downwardly tilted effective position wherein it will successively engage and advance every one of the adjacent six Geneva gears over a limited increment.

The six Geneva gears are adjusted to such rotary positions relative to each other that the depressions in the cams 508 of consecutive gears, counting backwards from the last gear 496, trail behind each other by rotary increments equal to the rotary increments by which the gears are advanced when effectively engaged by a memory pin. Initially, i.e., before an egg has been dropped into any of the pockets in the pocket row of a carton that is held below the egg supply conveyor, the Geneva gears

are in the position illustrated in FIG. 24A wherein the sixth Geneva 496, i.e. the gear that is last engaged by a memory pin in depressed condition, is in such a rotary position that the depression 510 of its cam 508 lies directly in front of the roller 512 of its associated switch 506, which is the switch that closes the power circuit of the last one 446 of the set of bucket opening solenoids 440 i.e., the solenoid on the downstream side of the carton supply conveyor. Thus, whenever the solenoid 524 depresses a memory pin 474, indicating that an egg on egg supply conveyor 100 approaches the packing station, consecutive engagement of said depressed pin with the consecutive Geneva gears 491 to 496 will advance all of said gears by a limited increment which remains without effect upon the switches 501 to 505 associated with the first five Geneva gears 491 to 495, respectively, but causes the roller 512 of the sixth switch 506 to drop briefly into depression 510 in the cam 508 of the sixth Geneva gear 496, as illustrated in FIG. 24B. This closes the switch 506 temporarily, and as a result thereof the last solenoid 446 in the battery of bucket-opening solenoids 440 is energized and projects its armature into the path of the noses 430 of the conveyor buckets 412 at the very moment when the bucket carrying the egg which started the described sequence of operations, approaches said solenoid 446, because the pins 474 of the control device 452 advance in synchronism with the advance of the buckets on the egg supply conveyor, as previously pointed out. Hence the egg will drop into the last pocket of the carton pocket row presented to the egg supply conveyor at the packing station.

As previously pointed out, however, passage of the above described memory pin 474 in depressed condition past the Geneva gears did not only advance the last Geneva gear 496, it also advanced each of the five preceding Geneva gears 491 to 495 by the same increment so that it is now the fifth Geneva gear 495 that holds the depression 510 of its cam 508 directly in front of the roller 512 of its associated switch 505. Hence, when the pin-activating solenoid 524 is again energized by the approach of an egg on the egg supply conveyor, and another memory pin 474 is depressed, said pin while advancing all the Geneva gears by equal rotary increments will cause the fifth Geneva gear 495 to effect closure of its respective switch 505 (FIG. 24C) with resultant energization of the fifth solenoid 445 in the battery of bucket-opening solenoids 440.

As best illustrated in FIG. 22, the fifth Geneva gear 495 is spaced from the sixth Geneva gear 496 by an angular interval that is smaller than the angular interval between each two consecutive memory pins 474 on rotor 476 by a ratio equal to the ratio of the linear interval between the center points of consecutive egg receiving carton pockets to the linear interval between the center points of consecutive buckets on the egg supply conveyor. Measured in angular distance, the fifth Geneva gear 495 is therefore closer to the sixth and last Geneva gear 496 than the angular interval between two directly consecutive memory pins 474 on rotor 476, and the second memory pin 474 in depressed condition must therefore travel a longer distance counted from the point of its rotary orbit that corresponds to the egg sensing point at which the described sequence of operations is started, to the fifth Geneva gear 495 than corresponds to the linear dimension of five consecutive buckets on the egg supply conveyor. As a result thereof, the bucket that carries the egg which caused depression of the second memory pin 474, will travel a distance slightly larger than five buckets from the egg sensing point until its representative pin 474 on rotor 476 effects energization of the fifth bucket opening solenoid 445 through actuation of the fifth Geneva gear 495. The bucket will therefore reach said solenoid 445 at the very moment when it projects its armature into the path of its nose 430, and hence the second egg supplied by conveyor 100 will drop into the

fifth carton pocket which is the second pocket counted from the downstream side of the packing station.

As the pin activating solenoid 524 depresses additional memory pins 474 indicative of the fact that additional eggs have come within the length of six buckets from the downstream side of the packing station, the Geneva gears 491 to 496 are consequently advanced by additional increments causing in succession closure of the fourth, third, second, and first switches 504, 503, 502, and 501, respectively, as illustrated in FIGS. 24D, 24E, 24F and 24G with resultant energization of the fourth, third, second and first bucket opening solenoids 444, 443, 442 and 441, respectively, which open succeeding buckets 412, as they carry eggs over the fourth, third, second and first carton pocket counted from the upstream side of the packing station. In this manner all the pockets in the pocket row of a carton presented to the egg supply conveyor by the carton supply conveyor are successively filled with eggs.

After all six switches 501 to 506 of the control mechanism 105 have been consecutively closed, and all six pockets of a carton pocket row presented to the egg supply conveyor have been filled with eggs, the carton which forms said pocket row must be shifted so that a consecutive row of pockets will lie below the egg supply conveyor, before another egg is released from said conveyor under control of mechanism 105. Means is therefore provided in accordance with the invention that causes advance of the carton underneath the egg supply conveyor so as to place an empty row of pockets underneath said conveyor whenever an egg has been dropped into the last pocket, of the preceding pocket row, which is the pocket on the upstream side of the packing station. Release of the egg that dropped into said last pocket was effected by operative engagement of a depressed memory pin 474 with the first Geneva gear 491 in the sequence of six Geneva gears, which engagement caused temporary closure of the switch 501 that energizes the first solenoid 441 of the battery of bucket opening solenoids 440 (FIG. 24G). After having actuated said first Geneva gear 491, the depressed pin 474 engages, and advances, consecutively all the remaining Geneva gears 492 to 496, as previously explained. The incremental advancement of the second Geneva gear 492 by said memory pin 474 is arranged to move the depression 510 in the cam 508 of said second Geneva gear 492 past the arched actuating end 530 of another normally open switch 532 (FIGS. 21, 22 and 24H) to cause brief closure thereof. The switch 532 is located between the first and second egg-releasing switches 501 and 502, respectively, as shown in FIGS. 21 and 22, and lies in the power circuit of the hereinbefore described ratchet release solenoid 210 (FIGS. 2, 18 and 25) below the clutch shaft 182 of the carton supply conveyor. As a result the solenoid 210 is energized and withdraws the latching pawl 202 from the ratchet 198 permitting said ratchet to follow the rotative force of the driving side of clutch 190, which causes engagement of said clutch. The carton supply conveyor 102 therefore, commences to advance moving the filled pocket row of the carton beyond the egg supply conveyor, while advancing the directly succeeding pocket row of the same carton, or the first pocket row of a directly succeeding carton as the case may be, into egg-receiving position below said egg supply conveyor. The switch 532 remains closed only for a fraction of the brief moment during which the memory pin 474 advances the second Geneva gear 492, and will have returned to open position by the time the memory pin that caused its closure disengages itself from the second Geneva gear 492. In consequence thereof the ratchet release solenoid 210 is energized for only the brief period necessary to withdraw the nose 206 of pawl 202 from whatever tooth of the ratchet 198 it engaged, and will immediately thereafter return into contact with the edge of the ratchet under the urgency of restore spring 208. The pawl 202

therefore engages the second tooth of the ratchet and causes disengagement of the clutch 190 so that rotation of the clutch shaft 182 is limited to an angular interval of 180° ; and depending upon which of the mutilated gears of the transmission 189 bring their toothed segments into operative engagement during the particular operational phase of the clutch shaft 182, the carton supply conveyor 102 is either advanced over the limited distance necessary to place the second pocket row of a carton into egg receiving position, or over the somewhat larger distance necessary to place the leading pocket row of a directly succeeding carton into egg receiving position. In the former case, when revolution of clutch shaft 182 as brought about by energization of the ratchet release solenoid 210, brings about effective engagement of the short gear segments of mutilated gears 234 and 240, the current operational phase of the clutch shaft 182 is also effective, after the conveyor 102 has come to a halt, to cause deposit of the stack of cartons in the magazine upon the conveyor, trip the carton retaining clamps so that they may grip the lowermost carton in the stack, and actuate the dispensing fingers to lift the stack above said lowermost carton in the manner described hereinbefore, so that said carton may freely move out from underneath the stack in the magazine during the next operational cycle of the clutch shaft.

Reverting to the control device 105, after the memory pin 474 that caused release of the last or sixth egg into the last pocket of a carton pocket row, has passed the second Geneva gear 492 where it initiated the above described operations for placing another row of pockets underneath the egg supply conveyor, it passes all the remaining Geneva gears 493-496 advancing them by rotational increments corresponding to the angular distance between two consecutive ones of their notches 497, and in passing the sixth Geneva gear 496 it places the same into its initial position as illustrated in FIG. 24A wherein the switch actuating depression 510 in its cam 508 lies again directly ahead of the actuating roller 512 of the power control switch 506 for the sixth egg-release solenoid 446. Hence, engagement of said sixth Geneva gear 496 by a subsequent memory pin 474 in depressed condition will cause said sixth egg releasing solenoid 446 to drop a first egg into the next pocket row presented to the egg supply conveyor. Thus, when another egg approaches the packing station and causes energization of the pin-depressing solenoid 524, the memory pin 474 depressed by energization of said solenoid will have to travel all the way to the sixth Geneva gear 496 (FIG. 22) before it causes energization of an egg-release solenoid. The next egg released from the egg supply conveyor is dropped into the sixth pocket on the downstream side of the new pocket row that has meanwhile been moved below the egg supply conveyor. Due to the fact that a pocket row receives its last egg from the egg supply conveyor at the upstream side of the packing station, and the next egg to be released from the egg supply conveyor—which is the first egg to be dropped into the succeeding pocket row—is dropped into the pocket on the downstream side of the packing station, ample time is provided for the operations that move a new pocket row into egg receiving position below the egg supply conveyor.

After a memory pin 474 in depressed condition has consecutively passed and actuated all six Geneva gears 491-496, it must be restored to ineffective position so that it may again be shifted to represent an approaching bucket 412 that carries an egg. For this purpose an upwardly slanting camming plate 534 is provided at the rear end of the rotor 476 adjacent the circular row of memory pins 474 (FIG. 22). Thus, after a depressed memory pin 474 has passed the sixth Geneva gear 476, it slides over the lower end of the camming plate 534, and as the pin continues its rotary course, it is cammed upwardly into its ineffective position.

To operate the described packing machine, the egg supply conveyor 100 is set into motion and also the motor (not shown) which supplies power to the carton supply conveyor 102, without however actually moving said conveyor owing to the fact that the latching pawl 202 engages tooth 216a of the ratchet 198 and in this manner maintains the clutch 190 in disengaged condition. A stack of cartons is placed into the magazine 104 and comes to rest upon the fingers 300a and 300b of the carton dispensing mechanism which are at this moment in their inwardly projected elevated position. In readying the machine for practical operation, it is then advisable to manually withdraw the pawl 202 from the ratchet 198 and thus permit rotation of the clutch shaft 182 until the lowermost carton in the stack has been deposited upon the conveyor 102 and has been advanced on said conveyor to a point, where its leading row of pockets is disposed below the upper run of the egg supply conveyor 100. Upon disengagement of the pawl 202 from ratchet tooth 216a the resulting revolution of clutch shaft 182 through an angle of 180° effects operative engagement of the toothed segment 228 of mutilated gear 226 in the conveyor drive transmission 189 with the toothed segment 230 of mutilated gear 232 on conveyor drive shaft 112 (FIGS. 9A and 9B). This is effective to advance the carton supply conveyor 102 by a distance that would move a carton from below the magazine to a position where its leading pocket row is in vertical alignment with the egg supply conveyor 100. Furthermore, the first half-revolution of clutch shaft 182 causes cam 308 upon said shaft to move its shallow rise 342 underneath its follower roller 322. As a result thereof the camming bars 332a and 332b are lifted into contact with the tapering ends of the triangular blocks 336a and 336b on the finger-supporting arms 312a and 312b, respectively, which readies the fingers 300a and 300b for withdrawal from underneath the carton stack within the magazine (FIGS. 26D and 26E). The directly succeeding half-revolution of clutch shaft 182 produces as its first effect operative engagement of the small toothed segment 236 of mutilated gear 234 in the conveyor drive transmission 189 with the toothed segment 238 of the mutilated gear 240 on conveyor drive shaft 112. This advances the conveyor 102 by a distance that would move the second pocket row of a carton that previously had its leading pocket row disposed below the egg supply conveyor, into egg-receiving position relative to said egg supply conveyor. The same advance of conveyor 102 is also effective to move a set of pusher plates 126a and 126b and a set of clamps 150a and 150b underneath the rear and front walls respectively of the carton magazine as illustrated in FIGS. 9C and 9D. At this time the cam 356 on clutch shaft 182 presents its sector 374 of reduced radius to its follower roller 358 (FIGS. 26A and 26B) which enables the spring 364 to hold the camming board 174 in the upwardly slanting position illustrated in FIG. 15B, and as a result thereof the clamps 150a and 150b that move underneath the magazine and align themselves to the front wall thereof assume the cocked position illustrated in said FIG. 15B. Similarly, as the pusher plates 126a and 126b approach the position illustrated in FIG. 15B, their tail members 142 ride on the lower portions 146 of the camming bars 144a and 144b, and as a result thereof said pusher plates assume a position wherein they are slightly more rearwardly inclined than during their actual carton propelling operation, and wherein they extend parallel to, yet remain spaced from the rear wall of a carton deposited upon the conveyor 102, as likewise illustrated in FIG. 15B.

The advance of the carton supply conveyor 102 as effected by operative engagement of mutilated gears 234 and 240 required less than 60° of the second half-revolution of the clutch shaft 182, and during the remaining 120° of the second half-revolution of said shaft, the mu-

tilated gear 234 operates to hold the conveyor 102 securely in the position illustrated in FIGS. 9D, 15B, 26A, 26B, 26C and 26D wherein a pair of pusher plates is positioned directly behind the rear wall of the magazine and a pair of retaining clamps is positioned underneath the front wall of the magazine, because during this phase in the operation of the machine the locking cam 254 of mutilated drive gear 234 engages the locking recess 256 in the edge of the mutilated gear 240 on conveyor drive shaft 112. Directly after the conveyor 102 has thus been locked against further movement, the cam 308 on clutch shaft 182 moves its steep rise 344 underneath its follower roller 322, which is effective to withdraw the fingers 300a and 300b from the magazine; and as a result thereof the whole stack of cartons in the magazine drops upon the conveyor 102 as shown in FIG. 26B. At the same time the cam 310 that formerly presented its sector 352 of increased radius to its follower roller 346, moves its sector 354 of reduced radius underneath said roller, and as a result thereof the springs 350a and 350b are able to lower the finger-supporting arms 312a and 312b to a position opposite the ends of the wedge-shaped recess in the floor of the second lowest carton in the magazine as illustrated in FIG. 26B. As pointed out hereinbefore, the steep rise 344 of cam 308 is of much shorter duration than the sector 354 of cam 310 and as a result thereof the fingers 300a and 300b will be projected into the magazine while they are still in lowered position so that they move underneath the second lowest carton in the magazine into the wedge-shaped recess in the floor thereof as shown in FIG. 26C. Directly thereafter the cam 356 presents its sector 376 of increased radius to its follower roller 358 as likewise shown in FIG. 26C, which forces the camming board 174 into the downwardly slanting position illustrated in FIG. 15C. As a result thereof the tail members 172 of the clamps underneath the front wall of the magazine lose support and the springs 166a and 166b snap the gripping tips 162 and 164 of the clamps over the leading wall of the lowest carton in the stack as shown in FIGS. 12 and 26C. Then, during the same half-revolution of clutch shaft 182 and while cam 356 continues to hold the camming board 174 in its ineffective position, the cam 310 moves again its sector 352 of increased radius underneath its follower roller 346, which forces the finger supporting arms 312a and 312b to return to their elevated position as illustrated in FIG. 26D. Thus, the stack of cartons in the magazine is lifted above the lowermost carton while said latter carton is securely held down upon the conveyor 102 by the clamps 150a and 150b. In this manner the lowermost carton is positively separated from the remaining stack. Then, as the clutch shaft 182 is allowed to perform a third half-revolution, said lowermost carton is advanced by effective engagement of the toothed segment 228 of mutilated gear 226 with the toothed segment 230 of mutilated gear 232 in the conveyor transmission 189 and during its advance, the carton remains firmly gripped by the clamps. However, as soon as the last-described advanced of conveyor 102 has moved the tail members 172 of the clamps out of reach of camming board 174, the cam 356 moves its sector 374 of reduced radius to its follower roller 358 enabling the spring 364 to restore the camming board to its effective clamp-cocking position, as shown in FIG. 26E. Thus the directly succeeding set of clamps is automatically placed into its cocked carton-receiving position as it moves underneath the front wall of the magazine.

With the leading pocket row of the first carton located in egg-receiving position relative to the egg supply conveyor, the latching pawl 202 is allowed to engage tooth 216b of ratchet 198 (FIG. 26E). Eggs may now be delivered into the buckets 412 of the egg supply conveyor 100. This may be done manually or it may be accomplished by suitable egg supply chutes and/or egg transfer mechanism such as are described in my co-pending patent applications Serial Nos. 358,621, and 400,466, filed on

June 1, 1953, and December 28, 1953, respectively. The latter is now Patent No. 2,895,274, July 21, 1959. From now on the egg packing machine of my invention operates completely automatically to pack eggs into cartons and will continue to do so as long as eggs are delivered into the buckets 412 of the egg supply conveyor and cartons are deposited into the magazine 104. As an egg approaches the packing station, it strikes against the yieldable sensing finger 454 (FIG. 19) and causes closure of switch 458 (FIG. 25) which energizes the solenoid 524 (FIGS. 21 and 22) causing its armature 526 to strike downwardly at the very moment when a memory pin 474 passes underneath. In this manner said memory pin 474 is depressed from ineffective to effective Geneva-gear advancing position. The shaft 462 of the control device 105 which turns as long as the egg supply conveyor 100 is in motion, turns the activated memory pin 474 in synchronism with the advance of the egg here under consideration toward and over the carton supply conveyor 102. As the particular pin 474 passes the six Geneva gears 491 to 496, it advances each of them by a small increment, and when advancing the last of said gears, it effects closure of switch 506 (FIG. 24B) causing energization of the last solenoid 446 (FIG. 25) in the battery of six solenoids that flank the egg supply conveyor 100 above the carton supply conveyor 102 (FIG. 19). Energization of said solenoid 446 projects its actuating edge 448 into the path of the nose 430 on the bucket 412 that carries the egg here under consideration causing the bucket to open up and drop the egg into the last pocket i.e., the pocket on the downstream side of the leading pocket row of the carton presented to the egg supply conveyor 100 by the carton supply conveyor 102.

Then, as soon as another egg approaches the packing station on the egg supply conveyor 100, and irrespective of whether this egg is seated in the directly succeeding bucket or whether several buckets are empty and it is a later bucket that carries the next egg, the cycle of operations repeats itself. Switch 458 is closed, solenoid 524 is energized, a pin 474 of rotor 476 corresponding to the bucket that carries the egg is depressed and the depressed pin advances all six Geneva gears 491 to 496 by a small increment. This time it is the fifth Geneva gear 495 whose rotation is effective to close its associated switch 505 (FIG. 24C) causing energization of the fifth bucket opening solenoid 445, and as a result thereof the second egg to be packed is dropped into the fifth pocket of the leading pocket row of the carton underneath the egg supply conveyor 100. In an analogical manner successive eggs cause successive energization of the fourth, third, second and first bucket opening solenoids 444, 443, 442, and 441 by closure of the switches associated with the fourth, third, second and first Geneva gears respectively, as illustrated in FIGS. 24D, 24E, 24F and 24G respectively, and accordingly the fourth, third, second and first pockets of the carton on the conveyor 102 are filled with eggs.

The activated memory pin 474 that caused release of an egg from the egg supply conveyor 100 above the pocket on the upstream side of the carton, by turning the Geneva gear 491 over a limited increment, as illustrated in FIG. 24G, causes also closure of switch 532 when it turns the next Geneva gear 492, as illustrated in FIG. 24H. Closure of switch 532 causes energization of the ratchet release solenoid 210 (FIGS. 2, 18 and 25) below the drive shaft 112 of the carton supply conveyor. The latching pawl 202 is therefore withdrawn from tooth 216b of the ratchet 198, the clutch 190 is engaged, and the transmission 189 advances the conveyor 102 by a distance determined by the angular width of the toothed segment 238 of mutilated gear 240 on the conveyor drive shaft 112, which places the second pocket row of the carton into egg receiving position below the egg supply conveyor (FIG. 26F). The same movement of the conveyor 102 places another set of pusher plates below the rear wall

of the magazine and another set of retaining clamps underneath the front wall of said magazine and forces said clamps into cocked position by engagement of their tail members 172 with the camming board 174 that is held in effective position by cam 356. As previously pointed out, the conveyor advance necessary to place the second pocket row of a carton into egg-receiving position requires less than 60° of the half-revolution of clutch shaft 182 that is initiated by withdrawal of the latching pawl 202 from tooth 216b of ratchet 198 and during the balance of the current half-revolution of clutch shaft 182 until the latching pawl 202 engages ratchet tooth 216a, cam 308 causes withdrawal of the fingers 300a and 300b from the magazine permitting the remaining stack in the magazine to drop into the space between the cocked retaining clamps 150a and 150b and the directly succeeding pusher plates 126a and 126b of conveyor 102, as shown in FIG. 26F, cam 310 effects descent of the fingers 300a and 300b to the level of the wedge-shaped recess in the floor of the second lowest carton, as is likewise shown in FIG. 26F and also in FIG. 26B, cam 356 trips the retaining clamps causing them to engage over the leading wall of the lowest carton in the stack, then cam 308 permits the fingers 300a and 300b to move underneath the second lowest carton in the stack (FIG. 26C) and cam 310 causes said fingers to rise to their original level and lift the stack of cartons in the magazine above the carton that is held upon the conveyor by the tripped clamps as shown in FIG. 26D. Already as these operations proceed and before the clutch shaft 182 has come to a halt with the latching pawl 202 engaged behind tooth 216a of the ratchet 198, the egg supply conveyor 100 may commence under the guidance of control mechanism 105 to drop eggs into the second pocket row of the first carton starting at the downstream side thereof; and after an egg has been deposited into the last pocket of said second pocket row on the upstream side of the carton, the ratchet release solenoid 210 is again energized and withdraws the latching pawl 202 from tooth 216a of the ratchet 198. The resultant long-distance advance of conveyor 102 advances the completely filled first carton such a distance beyond the egg supply conveyor 100 that its backwardly-folded lid will clear, and therefore be unable to interfere with the egg dropping operation of, said conveyor. At the same time the second carton is moved with its leading pocket row into egg-receiving position underneath the egg supply conveyor in the manner previously described. Another cycle in the operation of the egg-packing machine of my invention is under way.

While I have described my invention with the aid of a particular embodiment thereof, it will be understood that the invention is not limited to the specific constructional details illustrated and described which may be departed from without departing from the scope and spirit of the invention.

Also while the machine of the invention as illustrated in the accompanying drawings and as described in the specification was specifically devised and is employed for packing eggs, it will be understood that a machine embodying the principles of the invention may also be usefully employed to pack other articles, such as avocados, lemons, or other highly priced fruit.

I claim:

1. In an egg packing machine, a magazine adapted to receive a stack of superposed cartons, a mechanism for dispensing cartons individually from the magazine comprising arms disposed at opposite sides of the magazine, inwardly projecting fingers mounted upon said arms, and means for actuating said arms to move said fingers between a position projected into said magazine and a position laterally withdrawn from said magazine and also between an elevated position and a lowered position, said actuating means including a first transverse shaft rotatable about a horizontal axis, means mounting said arms upon said first shaft for rotation therewith and also for

rotation about axes substantially perpendicular to the axis of said first shaft, a pair of blocks, each block being secured to the inner face of one of said arms and having an inwardly inclined inner surface disposed directly opposite the inclined surface of the other block, a second transverse shaft, camming bars firmly secured to said second shaft with their ends in contact with the inner surfaces of said triangular blocks, means operable to turn said second shaft between a position wherein said bars are in engagement with the outermost portions of the inclined surfaces of said blocks and a position wherein said bars are in engagement with the innermost portions of the inclined surfaces of said blocks whereby to swing said arms to said withdrawn position, means urging said arms in a transverse direction toward each other against the action of said camming bars, and means operable to turn said first transverse shaft about said horizontal axis to move said arms bodily in a vertical direction.

2. In an egg packing machine, an open bottomed magazine adapted to receive a stack of superposed cartons, a mechanism for dispensing cartons individually from the magazine comprising arms disposed at, and parallel to, opposite sides of the magazine, inwardly projecting fingers mounted upon said arms, and means for actuating said arms to move said fingers between a position projected into said magazine and a position laterally withdrawn from said magazine and also between an elevated position and a lowered position, said actuating means including a first transverse shaft rotatable about a horizontal axis, means mounting said arms upon said first shaft for rotation therewith and also for rotation about axes substantially perpendicular to the axis of said shaft, means operable to turn said first shaft between a position wherein the fingers on said arms are elevated and a position wherein the fingers on said arms are lowered, blocks secured to the inner faces of said arms and having inwardly inclined upright surfaces, a second transverse shaft, camming bars firmly secured to said second shaft for movement in a vertical direction as said second shaft is rotated, said bars having portions in contact with the inner upright surfaces of said blocks, and means operable to turn said second shaft between a position wherein said bars are in engagement with the outermost portions of said upright inclined surfaces of said blocks and a position wherein said bars are in engagement with the innermost portions of said surfaces whereby to swing said arms outwardly to said withdrawn position, and means urging said arms in a transverse direction toward each other against the action of said camming bars.

3. Apparatus for dispensing cartons or the like comprising a magazine having an open lower end and slots in opposed walls at the lower end thereof and being adapted to receive a stack of superposed cartons, lifting arms disposed at opposite sides of the magazine, inwardly projecting fingers mounted upon said arms, means mounting said arms for movement in a vertical plane, means for actuating said arms to move said fingers between a position projected through said slots into said magazine beneath a stack of cartons therein and a position laterally withdrawn from said magazine, said actuating means including means mounting said arms for rotation about substantially vertically extending axes, a block of triangular contour secured to the inner face of each of said arms and each block having an inwardly slanted inner surface, a transverse shaft, camming bars firmly secured to said shaft with each bar in contact with the inner surface of one of said triangular blocks, means operable to turn said shaft from a position wherein said bars are in engagement with the outermost portions of the slanted surfaces of said triangular blocks and a position wherein said bars are in engagement with the innermost portions of the slanted surfaces of said triangular blocks whereby to swing said arms outwardly away from said magazine and remove said fingers from beneath a carton of said stack to permit the carton to be dispensed through the open lower end of the magazine, and cam means operatively connected to said

lifting arms and connected with said shaft turning means to move said lifting arms in a vertical plane in timed relation with the turning of said shaft.

4. Apparatus for dispensing cartons or the like comprising a magazine having an open lower end and a pair of side walls each having a vertical slot, said magazine being adapted to receive a stack of superposed cartons, lifting arms disposed at opposite sides of said magazine, means mounting said lifting arms for movement in a vertical plane and for movement toward and away from said magazine, a finger on each arm projecting inwardly toward said magazine, spring means connected to said arms and urging said arms inwardly toward said magazine, means for actuating said arms to move said fingers between a stack-supporting position projecting through said vertical slots into said magazine and a position withdrawn from said magazine, said actuating means comprising a shaft mounted for rotation about a horizontal axis, a cam carried by each arm on the side of the arm facing inwardly toward said magazine, cam actuating arms carried by said shaft and arranged to engage said cams during rotation of said shaft and force said arms away from said magazine to withdraw said fingers from stack-supporting position, permitting a carton to drop out the open lower end of said magazine, and rotatable drive means connected in driving engagement with said shaft and with said lifting arms and arranged to move said lifting arms in said vertical plane in timed relation with the movement of said fingers inwardly and outwardly of said magazine.

5. In an egg packing machine, an open bottomed magazine adapted to receive a stack of superposed cartons, a mechanism for dispensing cartons individually from the magazine comprising arms disposed at, and parallel to, opposite sides of the magazine, inwardly projecting fingers mounted upon said arms, and means for actuating said arms to move said fingers between a position projected into said magazine and a position laterally withdrawn from said magazine and also between an elevated position and a lowered position, said actuating means including a first transverse shaft rotatable about a horizontal axis, means mounting said arms upon said first shaft for rotation therewith and also for rotation about axes substantially perpendicular to the axis of said shaft, first control means operable to turn said first shaft between a position wherein the fingers on said arms are elevated and a position wherein the fingers on said arms are lowered, blocks secured to the inner faces of said arms and having inwardly inclined upright surfaces, a second transverse

shaft, camming bars firmly secured to said second shaft for movement in a vertical direction as said second shaft is rotated, said bars having portions in contact with the inner upright surfaces of said blocks, and second control means operable to turn said second shaft between a position wherein said bars are in engagement with the outermost portions of said upright inclined surfaces of said blocks and a position wherein said bars are in engagement with the innermost portions of said surfaces whereby to swing said arms outwardly to said withdrawn position, said first and second control means including a control shaft and cam means operatively connected between said control shaft and said first and second shafts to operate said first and second shafts in timed relation.
